UNITED STATES PATENT OFFICE.

WALTER O. AMSLER, OF EDGEWOOD, PENNSYLVANIA.

ANNEALING-FURNACE OR LEER.

1,351,323.

Specification of Letters Patent. Patented Aug. 31, 1920.

Application filed November 29, 1918. Serial No. 264,491.

To all whom it may concern:

Be it known that I, WALTER O. AMSLER, a citizen of the United States, residing at Edgewood, in the county of Allegheny and State of Pennsylvania, have invented certain new and useful Improvements in Annealing-Furnaces or Leers, of which the following is a specification.

In the accompanying drawings which illustrate an application of my invention,

Figure 1 is a longitudinal vertical sectional view of an annealing furnace or leer embodying my invention;

Fig. 2, a horizontal sectional view, the section being taken on line 2—2 of Fig. 1;

Fig. 3, a vertical sectional view taken on line 3—3 of Fig. 1;

Figs. 4 and 5, detail perspective views of tiles employed; and

Fig. 6, a diagram showing a comparison of temperature cycles.

The prime object of the present invention is to provide a new and improved annealing furnace or leer of the continuous type and particularly a leer designed for annealing glass articles, whereby the articles to be treated may be first subjected to a temperature above the critical point and then be subjected to a uniform gradual drop in temperature.

In the usual continuous heat treating furnaces employed for annealing glass articles, a relatively short fire box or heating chamber is employed at the forward end of a tunnel-like structure for the purpose of subjecting the articles to a desired heat, and then depending upon the heat which travels back through the remainder of the tunnel to provide a sufficient drop in temperature to anneal the articles as they are passed through the furnace. The temperature cycle of a furnace of this character is shown by the dotted lines in the diagram, Fig. 6, and it will be noted that this shows a dropping of the temperature gradient in such a manner as to provide unsatisfactory and incomplete annealing and consequently considerable loss.

By means of the present invention I am enabled to overcome the disadvantages encountered in operating the above described leer, and to obtain a temperature cycle illustrated by the full line in Fig. 6. By means of the construction, arrangement and com-

bination of the muffle, combustion chamber, flues and temperature controlling means, as embodied in my invention, I am enabled to provide a temperature zone sufficiently high to relieve all internal stresses in the articles being treated, and then a zone or zones in which the temperature gradually and uniformly drops to near atmospheric, whereby the articles will be first heated to the critical point in the first zone and then gradually and uniformly cooled in the second or following zones.

Referring to the drawings, 2 designates the side walls of the furnace, 3 and 4 front and rear walls, and 5 the arched top. These elements are of the usual brick-work construction and are disposed on a suitable foundation 6. The furnace illustrated is of the continuous type, and communicates at one end through an opening 7 in the rear wall 4 with a tunnel 8.

It will be noted that I employ a furnace of considerable more length than the usual and well known furnaces of the class to which my invention relates, and that I also provide a muffle or an annealing chamber of great length, whereby I am enabled, in conjunction with the combination and arrangement of parts hereinafter described, to effect a highly efficient temperature control, thereby making it possible for the material to be treated under much more favorable conditions than has heretofore been the case.

The muffle or annealing chamber 9 has its side walls constructed of tiles 10 and 11, its arch of tiles 12, and its bottom of tiles 13. Forming the side walls of two tiles, that is to say, the side wall tile proper 10 and the skew tile or block 11, and resting the arch on the skew tiles as shown, provides a highly satisfactory construction, preventing cracks developing in the tiles, and preventing products of combustion from entering the muffle.

Heretofore, the side walls of muffles of this type have been constructed of a series of single tiles, the result being that cracks or breaks develop in the side tiles adjacent the skew lines. By providing the short tile 11 and the tongue and groove joint 14 between tiles 10 and 11, the masonry is permitted to give slightly under the arch thrust and the skew tile to move slightly on the tile 10.

In addition to the tongue *a* and groove *b*, tile 10 is formed with outwardly projecting longitudinally extending flanges or ribs *c*. Flanges *c* are designed for strengthening 5 the tiles and also for the purpose of co-operating with the furnace wall to form flues, as hereinafter described.

15 designates a gas or fuel conduit, and 16 a suitable gas burner in communication 10 with the conduit 15 and with the combustion chamber 17 disposed over the top of the muffle. The space between the top of the muffle and the furnace wall beyond the combustion chamber 17 is divided into a plurality of compartments by partition walls 18 and 18^a.

Interposed between the interior of the side walls of the furnace and the muffle, I provide a series of flues 19, said flues being 20 formed by the flanges *c* of the series of tiles 10 and the interior surface of the side walls of the furnace. As illustrated, these flues are disposed throughout the length of the furnace and are designed for the purpose 25 of permitting the passage of products of combustion from the combustion chamber 17 down into a centrally disposed flue 20, and from the flue 20 upwardly into the compartment 17^a of the space above the muffle, and thence again downwardly into said flue 20. Flue 20, like the space above the muffle, is divided into a plurality of compartments by means of the vertically extending partition wall 21. 17^b designates 30 a compartment above the muffle formed between wall 18^a and furnace wall 4 into which the products pass prior to reaching the chimney.

22 designates a chimney through which 40 the waste products of combustion escape from the interior of the furnace, said chimney being provided with a damper device 23.

For the purpose of controlling the passage of the products of combustion through 45 the side flues 19, I provide each flue with a damper 24, adapted to be operated on the outside of the side walls of the furnace. By means of these dampers it will be evident that I am enabled to conveniently regulate 50 the passage of heat products through the flues and in turn control the temperature within the muffle chamber at will.

By employing the partition walls 18 and 18^a extending across the space above the 55 muffle, the wall 21 across the central draft flue and the vertically extending flues 19, I provide four passes for the travel of the products through the furnace, first, from the combustion chamber 17 to the common 60 flue below the muffle; second, a pass from the flue upwardly to the compartment 17^a; third, downwardly from the compartment 17^a to said flue 20; and, fourth, from flue 20 to compartment 17^b and thence to chimney.

65 It will be understood that the materials to

be treated are passed through the muffle or annealing chamber, and for this purpose I have provided a series of roller supports 26, on which a pan or a series of pans 27 are drawn through the furnace by any suitable means, not shown.

What I claim is:

1. In an annealing furnace or leer, an elongated muffle, a chamber disposed over the top of the muffle, said chamber having 75 a partition wall dividing it into a combustion chamber and a compartment beyond the combustion chamber, a flue below the muffle, side flues connecting the combustion chamber and compartment and the flue below the muffle, and means for controlling the passage of products of combustion through said side flues.

2. In an annealing furnace or leer, an elongated muffle, a combustion chamber disposed over the top of the muffle, a flue below the muffle, side flues connecting the combustion chamber and the flue below the muffle, said side flues formed by projections extending from the muffle wall to the furnace wall, and means for controlling the passage of products of combustion through 90 said side flues.

3. In an annealing furnace or leer, an elongated muffle, a longitudinally extending 95 chamber disposed over the top of the muffle, a laterally extending partition dividing the chamber into two compartments, a common central longitudinally extending flue below the muffle, said latter flue having a partition 100 wall dividing the flue into two compartments, and side flues connecting the compartments above the muffle and the central flue, said flues co-operating with the chamber to provide a plurality of passes for the 105 products of combustion during their travel through the furnace.

4. In an annealing furnace or leer, a muffle, a combustion chamber disposed over the top of the muffle, a flue below the muffle, 110 said muffle having its side walls including flanged tiles having the flanges thereof in contact with the side walls of the furnace to form vertically extending side flues connecting the combustion chamber and the 115 flue below the muffle.

5. In an annealing furnace or leer of the continuous type, an elongated muffle, a combustion chamber disposed over the top of the muffle, means for circulating a heating 120 medium over and around the muffle, said means including partition walls above and below the muffle arranged and adapted to provide a plurality of passes surrounding the muffle and a plurality of heat zones with- 125 in the muffle whereby one of said zones may be maintained at a temperature above the critical temperature and another at a pre-determined uniform heat gradient.

6. In an annealing furnace or leer, a 130

muffle having its sides and arch formed of tiles disposed therein, said muffle having its side walls formed of a series of side wall tiles proper and a series of independent 5 skew tiles, the arch of the muffle being supported by the skew tiles.

7. In an annealing furnace or leer, a muffle having its sides and arch formed of tiles disposed therein, said muffle having its 10 side walls formed of a series of side wall tiles proper having projecting flanges and a series of independent skew tiles, the arch of the muffle being supported by the skew tiles, said flanges co-acting with the furnace, 15 walls to provide vertically extending side flues.

8. In an annealing furnace or leer, a muffle, a combustion chamber disposed over the top of the muffle, a flue below the muffle, 20 side flues connecting the combustion chamber and the flue below the muffle, said flues formed by projections extending from the muffle wall to the furnace wall.

9. In an annealing furnace or leer, a muffle positioned within the furnace to form 25 a space between the top of the muffle and furnace, a partition wall extending laterally across the space to form a combustion chamber and a compartment beyond the combustion chamber, a flue below the muffle, and side flues connecting the combustion chamber, 30 a flue below the muffle, and side flues connecting the combustion chamber.

ber and compartment and the flue below the muffle.

10. In an annealing furnace or leer, an elongated muffle positioned within the furnace to form a space between the top of the muffle and the furnace, partition walls dividing the space into a combustion chamber and a plurality of compartments beyond the combustion chamber, a flue below the muffle, 35 and side flues connecting the combustion chamber and compartment and the flue below the muffle.

11. In an annealing furnace or leer, an elongated muffle, a chamber disposed over the top of the muffle and having a partition wall dividing it into a combustion chamber and a compartment in communication with the combustion chamber, a flue below the muffle, and side flues connecting the combustion chamber and said compartment with the flue below the muffle, whereby heating gases are passed from the combustion chamber down into the flue below the muffle and thence upwardly into said compartment. 40 50 55

In testimony whereof I affix my signature in presence of two witnesses.

WALTER O. AMSLER.
